US0D1074526S

(12) **United States Design Patent** (10) **Patent No.:** **US D1,074,526 S**
(45) **Date of Patent:** **** May 13, 2025**

(54) **BICYCLE COVER FOR TRANSPORTATION**

(71) Applicant: **Jinhua Runhaifeng Technology Co., Ltd.**, Jinhua (CN)

(72) Inventor: **Jinshu Jiang**, Nanjing (CN)

(**) Term: **15 Years**

(21) Appl. No.: **29/898,322**

(22) Filed: **Jul. 26, 2023**

(51) **LOC (15) Cl.** **12-16**

(52) **U.S. Cl.**

USPC **D12/402**

(58) **Field of Classification Search**

USPC D12/114, 400-403, 409, 410; D6/610; D21/834; D25/18
